UNITED STATES PATENT OFFICE.

ROBERT E. HUMPHREYS, OF WHITING, INDIANA, ASSIGNOR TO STANDARD OIL COMPANY, OF CHICAGO, ILLINOIS, A CORPORATION OF INDIANA.

PROCESS OF DISTILLING PETROLEUM.

1,122,003.

Specification of Letters Patent.

Patented Dec. 22, 1914.

Application filed January 20, 1914. Serial No. 813,220.

To all whom it may concern:

Be it known that I, ROBERT E. HUMPHREYS, a citizen of the United States, residing at Whiting, in the county of Lake 5 and State of Indiana, have invented a new and useful Improvement in Processes of Distilling Petroleum, of which the following is a specification.

My invention consists in an improved process for distilling petroleum. Its object is to furnish a procedure for the treatment of fuel-oil or other hydrocarbons mainly of the paraffin series, having a relatively high boiling point, *i. e.* upward of 500° F., by 15 means of which to obtain products of lower boiling points, such as gasoline.

A desirable apparatus for use in the practice of my process is shown in the accompanying drawings, in which—

20 Figure 1 is a sectional side elevation of the preferred still, and Fig. 2 is a section on the line 2 of Fig. 1.

The still is generally indicated by the character 3, and is provided with covered manholes 4 and 5 in one end and its top, respectively. A vapor-outlet pipe 6 leads from the top of the still to a condenser (not shown), and a valved draw-off pipe 7 for the liquid residue leads from near the 30 still-bottom through the top. Insulating material 8 covers the still, as usual; and the still surmounts a brick structure forming a furnace 9, from which the hot products of combustion pass over a bridge-wall 10 and discharge through a flue 11.

35 The apparatus as so far described is of known construction, and may be used for the distillation of high-boiling point hydrocarbons, such as fuel-oil, to produce therefrom low-boiling point products, such as gasoline, in accordance with known methods of procedure as set forth, for instance, in the patents to William M. Burton, No. 1,049,667, January 7, 1913, and No. 1,055,707, 40 March 11, 1913. In such procedure, a liquid body of fuel-oil or other high boiling point hydrocarbon is subjected to a pressure of about 4 to 5 atmospheres, so as to require a temperature of from 650 to 850° F. for 45 its distillation, the pressure exerted being the back pressure of the distilled vapors themselves. Such pressure may be conveniently obtained in the still by the use of a controlled outlet for the gaseous products of distillation.

In the practice of the known process, thus briefly outlined, and with the apparatus as so far described, it has been found impracticable to distil more than about one-third of the charge before it becomes necessary to draw off the residue. This is because a thin layer of coke forms gradually on the hot lower inner surface of still and after a certain time, (about twenty six hours in commercial practice) the layer is so thick as to produce overheating, buckling and possible burning out of the still-bottom if the distillation be not then stopped. This coking action thus imposes a fairly definite time limit on the run.

70 I have discovered that if the high-boiling point hydrocarbons, while at the prescribed temperature and pressure, be brought into contact with relatively extended surfaces of practically any material which will withstand the temperature, a catalytic action is set up, the conversion of the heavy molecules into the lighter ones being apparently greatly expedited thereby. The catalytic surfaces may be of metal, such as steel, 75 brass or copper, either in the form of plates or gauze, although mineral fibers such as asbestos or glass wool seem to be equally effective. The action of those surfaces, like that of most catalysts, is obscure, but it is 80 a fact that when the catalyzing surfaces are used, the action is so augmented that sixty-five to seventy per cent. of the contents of the still can be satisfactorily transformed 85 in the desired manner before it becomes 90 necessary to draw off the residue, while without them, only about one-third of the charge can be so transformed, the residue in any event having been modified in character, as well known and set forth in the 95 later Burton patent referred to above.

When it is considered that a standard type of still in use for the purpose, has a capacity of eight thousand gallons, and that these stills are run in batteries of twelve 100 or more, it will be seen that there is a very material advantage in the use of the catalyzing surfaces.

105 It seems to be immaterial whether the hydrocarbon is in liquid or vapor form when brought into contact with the surfaces. The surfaces may, therefore, be provided in the liquid, one means of supplying them consisting of the plates 12 (Fig. 2) pivoted at 13 and adapted to interlock, as shown.

so as to form a covering conforming more or less to the curvature of the still-bottom, but so supported as to leave ample space for the free circulation of the liquid when boiling. The surfaces may, however, be provided in the form of plates 14 suspended above the liquid level (indicated by the dotted line 15), and they seem to be equally effective for the purpose. The two series 10 of plates may be used, as shown, or either series may be used without the other, the form, disposition and arrangement of catalytic plates being apparently immaterial to the success of the operation.

15 What I claim as new and desire to secure by Letters Patent is—

1. The method of treating the liquid portion of the paraffin series of petroleum distillates having a boiling point of upward of 500° F. to obtain therefrom low boiling point products of the same series, which consists in distilling off a portion only of a liquid body of the said hydrocarbons at a temperature of from about 650° F. to 850° F. under a pressure of upward of four atmospheres, in the presence of extensive catalytic surfaces, condensing the distillate, and leaving a considerable proportion of liquid residue which has been subjected to the action of the said surfaces.

2. The method of treating the liquid portion of the paraffin series of petroleum distillates having a boiling point of upward of 500° F. to obtain therefrom low boiling point products of the same series, which consists in distilling off a portion only of a liquid body of the said hydrocarbons at a temperature of from about 650° F. to 850° F. under a pressure of upward of four atmospheres, subjecting the contents of the still

during distillation to the catalytic action of surfaces supported in the still, condensing the distillate, and leaving a considerable portion of liquid residue which has been subjected to the action of the said surfaces.

3. The method of treating the liquid portion of the paraffin series of petroleum distillates having a boiling point of upward of 500° F. to obtain therefrom low boiling point products of the same series which consists in distilling off a portion only of a liquid body of the said hydrocarbons at a temperature of from about 650° F. to 850° F. under a pressure of upward of four temperatures, subjecting the contents of the still 55 during distillation to the catalytic action of metal plates supported in the still, condensing the distillate, and leaving a considerable proportion of liquid residue which has been subjected to the action of said plates. 60

4. The method of treating the liquid portion of the paraffin series of petroleum distillates having a boiling point of upward of 500° F. to obtain therefrom low boiling point products of the same series, which consists in distilling off a portion only of a liquid body of the said hydrocarbons at a temperature of from about 650° F. to 850° F. under a pressure of upward of four atmospheres, subjecting the contents of the still 70 during distillation to the catalytic action of plates immersed in the liquid, condensing the distillate, and leaving a considerable proportion of liquid residue which has been subjected to the action of the said surfaces. 75

ROBERT E. HUMPHREYS.
